CLAIM

The ornamental design for an animal waste bag dispenser and collection station, as shown and described.

DESCRIPTION

FIG. 1 is a perspective view showing an animal waste bag dispenser for an animal waste bag dispenser and collection station according to one embodiment;

FIG. 2 is another perspective view;

FIG. 3 is a rear view;

FIG. 4 is a front view;

FIG. 5 is a left side view;

FIG. 6 is a right side view;

FIG. 7 is a top view; and,

FIG. 8 is a bottom view of the animal waste bag dispenser for an animal waste bag dispenser and collection station according to one embodiment.

The ornamental design that is claimed is shown in solid lines in the drawings. Any broken or phantom lines in the drawings form no part of the claimed design. Specifically, the broken lines of FIGS. 1-8 are for the purpose of illustrating one example of possible environmental features of the embodiment illustrated therein.
